UNITED STATES PATENT OFFICE.

CHARLES D. McDONALD, OF CHICAGO, ILLINOIS.

AUTOMATIC STOP DEVICE FOR STRIP-INSERTING MECHANISM OF POWER PRESSES.

Application filed January 20, 1923. Serial No. 613,808.

To all whom it may concern:

Be it known that I, CHARLES D. McDONALD, a citizen of the United States, and a resident of Chicago, Cook County, and 5 State of Illinois, have invented certain new and useful Improvements in Automatic Stop Devices for Strip-Inserting Mechanism of Power Presses, of which the following is declared to be a full, clear, and ex- 10 act description.

This invention relates to automatic stop devices for the strip inserting mechanism of power presses, and its primary object is to provide a simple, efficient and practical 15 device for arresting the movement of the strip inserters, (which insert the strips into the feed slot) in case a strip is not in the proper position to be inserted at the time that the strip inserters are actuated. The 20 invention has been designed for use in connection with automatic power presses, and it sometimes happens in machines of this kind that the suction cups, or other means for lifting the metal strips one at 25 a time, become inoperative, so that the strip is not moved to the proper position for insertion into the feed slot. The work is then apt to be jammed when the strip inserters engage the work, which makes it 30 necessary to stop the press, thereby causing loss of time and loss of material. One object of this invention is to provide means, operating under the influence of the strips themselves, to arrest the movement of the 35 strip inserters unless a lifted strip is in proper position to be inserted into the feed slot. It sometimes happens that one of the several suction cups, or other strip lifting device, becomes temporarily inoperative, 40 with the result that one end of the strip is permitted to sag, whereas the other parts of the strip are held in proper position for insertion into the feed slot, and one object of this invention is to provide automatic 45 means operating to arrest movement of all of the strip inserters in case either of the end suction cups or other strip lifting devices, becomes inoperative and fails to lift either end of the strip into proper position 50 for insertion in the feed slot. Other objects and advantages will occur in the course of this specification and with all of said objects and advantages in view, this

invention consists in a device for arresting movement of the strip inserters and having 55 means operated by a properly lifted strip, to permit the strip inserters to function. It further consists in a stop device for the strip inserters having a movable dog normally located in the path of movement of 60 a moving element of the strip inserting mechanism, and means associated with the end suction cups or other strip lifting devices, and operated by a properly lifted strip to move the dog out of the path of 65 movement of said movable element of the strip inserting mechanism. It further consists in a plurality of movable dogs normally located in the path of movement of 70 the end strip inserters and having members, one associated with each suction cup, or other strip lifting device, for moving the associated dog out of the path of movement of the strip inserters whenever the strip is lifted into proper position for insertion into the feed slot. It further consists in the several novel features herein- 75 after fully set forth and particularly defined in the claims.

The invention is clearly illustrated in 80 the accompanying drawings, in which:

Fig. 1 is a side elevation of an automatic power press equipped with an automatic stop device for the inserting mechanism, embodying a simple form of the present invention; Fig. 2 is a front view of the said press mechanism looking in the direction of the arrow 2 in Fig. 1; Fig. 3 is a detail, front view of one of the suction cups, the associated strip inserter and the associated stop 85 device, showing the parts in position when a strip has been lifted into proper place for insertion into the feed slot; Fig. 4 is a view similar to Fig. 3 but showing the stop device in another position and Fig. 5 90 is a plan of the parts seen in Fig. 3 with the suction cup stem shown in cross section.

Referring to said drawings, which illustrate the invention applied to an automatic power press similar to the press shown in 100 several of the prior patents on the presses issued to the McDonald Machine Co., and in my prior Patent No. 1,039,565 dated September 24, 1912, the reference character 10 designates the power press mechanism, 11 105 the table upon which the strips *a* of metal

or other work is laid and from which the strips are lifted one at a time and thereafter inserted through a feed slot 13 into position to be fed to the dies in a step by step manner; 12 designates the feed bar which feeds the inserted strips to the dies; 14, 14^a designate the suction cups or other strip lifting devices; 15, 15^a designate stems which carry said suction cups; 20 a rod or bar connected to the stems of the several suction cups; 21 a link; 19 a lever connected to said link and 18 a link connected to the other end of the lever and to a crank wheel 17 which is driven by the power mechanism 16 of the press. The suction cup stems 15, 15^a, are guided in bearing brackets 16 mounted on the frame of the press. A vacuum is created in the suction cups at the time they engage the strips and said vacuum is broken 20 when the suction cups reach the upper limits of their strokes, and said vacuum is produced by a vacuum pump connected by a flexible tube 20^a the rod 20 and stems 15 (which are tubular) to the suction cups. 25 Adjacent the end suction cups 14 are the strip inserters or strip inserting arms 50, which have rods 40 that are slidably mounted in bracket 40^a mounted on the frame of the press, and said 30 strip inserting arms are reciprocated in timed relation to the movement of the suction cups, by mechanism, here shown as comprising collars 44 secured on the rods 40 of the strip inserting arms, links 42 connected to said collars, rocker arms 41 connected to said links, a rock shaft 45 on which said rocker arms 41 are secured, a rocker arm 41^a, on the rock shaft 45, a rocker member 46 connected to said rocker arm 41^a by a link 47 and a cam 48 cooperating with a roller 46^a on said rocker member 46 to move the inserting arms back after they have performed their work. A spring 49 secured to the press frame and to the rocker 45 arm 41^a imparts the working strokes to the strip inserting arms. All of the mechanism thus far described is common and well understood and is more fully set forth in detail in many of the prior patents above referred to, and requires no further detailed description so far as this specification is concerned. It will be understood from the above that at the time that the strips are lifted to a position in line with and in front of the feed slot, the roller 46^a of the rocker member 46 runs off the high part of the cam 48, and the spring 49 thereupon moves the rocker arm 41^a and therewith the rock shaft 45, rocker arms 41 and links 42, bringing the strip inserting arms 50 into engagement with the edge of the lifted strip, and forcing said strip into the feed slot 13, in position to be acted on by the feed mechanism.

65 Located in the path of movement of one

of the moving elements of the strip inserting mechanism is a stop device, normally acting to arrest movement of said moving element and having means associated with each end suction cup for moving said stop device out of the path of movement of said moving element of the strip inserting mechanism whenever a strip is lifted into proper position for insertion into the feed slot. In the 75 specific form of the invention illustrated in the accompanying drawings, the stop mechanism comprises dogs 51, one pivotally mounted upon each end suction cup guide bracket 16, to move in a vertical plane. As 80 shown, studs screws 52 pivotally secure each dog upon the guide bracket. One end of each dog projects beyond its bracket 16 and is located in the path of movement of the collar 44 of the associated strip inserter, as 85 clearly seen in Fig. 4. Movement of the strip inserter in the direction of the arrow in Fig. 5 is arrested by the dog 51 whenever it is in the operative position seen in Fig. 4.

Associated with each dog 51, is a dog actuating member which, as illustrated, comprises a pin 53 slidably mounted in a bearing bracket 54 which is secured to the associated suction cup guide bracket 16, and said pin has a collar 55 secured thereon at a place adjacent its upper end, which collar normally rests upon the top of the bracket 54 and supports the pin therein. The free end of the pin 53 engages with the under side of the dog 51 and forms the support for the free end thereof. Except when moved upward by any force, the collar 55 rests upon the bracket 54 and supports the pin 53 in the position seen in Fig. 4 where its upper end supports the free end of the dog 51 in a position located in the path of travel of the collar 44. The collar and dog may have correspondingly beveled portions 56, 56^a to facilitate the movement 100 of the collar past the dog when being returned to its outer position after having performed its work. When the pin is supported by the collar, its lower end projects a short distance below the lower face of the suction cup 14, as seen in Fig. 4 and when moved upward, (until the lower end of the pin is flush with the lower face of the suction cup,) it raises the free end of the dog 51 out of the path of travel taken by the collar 44, thereby permitting said collar and therewith the strip inserter to move in a direction to insert a properly lifted strip into the feed slot. Fig. 3 shows a strip *a* lifted by the suction cup into proper position where it may be inserted into the feed slot by the strip inserter 50. It will be clearly seen from an inspection of this figure that by reason of the engagement of the lifted strip *a* with the bottom of the 115 120 125 130

pin 53, the latter has been raised and therewith the dog 51 has been moved upward out of the path of travel of the collar 44.

In the operation of the device, the suction cups lift the strips *a* one at a time, and when the suction cups are working normally, they lift the strip into a position in line with the feed slot 13, after which the roller 46^a of the strip inserting mechanism runs off the high part of the cam 48, and the spring 49 moves the strip inserting arms against the edge of the strip and forces the strip into the feed slot. In case either end suction cup fails to function properly when it is lifting a strip, and as a consequence permits one of the ends thereof to sag, that end of the strip fails to engage and raise the pin associated with said suction cup, thereby permitting the associated dog 51 to remain in its operative position obstructing movement of an associated strip inserting arm. Inasmuch as the strip inserting arms at both ends of the feed table are fixedly connected to the rock shaft 45, both strip inserting arms are prevented from moving in case one or the other of them is prevented from so moving. In this condition, when the roller 46^a runs off the high part of the cam 48, the spring 49 merely pulls upon the rocker arm 41^a but inasmuch as neither strip inserting arm is capable of any movement, the parts remain neutral, thereby permitting the improperly lifted strip to fall back upon the pile of strips. In case the suction cups fail to properly function during the next cycle of operation, the press is stopped and the necessary repairs are made.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new and desire to secure by Letters Patent:

1. In a power press, the combination of strip lifters, strip inserting mechanism operating to insert a lifted strip into a feed slot of the press, and control means for said strip inserting mechanism, having a stop member normally located in the path of a moving element of said strip inserting mechanism, and strip actuated elements associated with the strip lifters and arranged to move the stop member out of the path of movement of said moving element of the strip inserting mechanism, whenever actuated by a lifted strip.

2. In a power press, the combination of strip lifters, strip inserting mechanism having strip inserting arms, and control means for said strip inserting arms, said control means having a stop member located in

the path of movement of a moving element of said strip inserting mechanism, and strip actuated elements arranged to move the stop member out of the path of movement of said moving element of the strip inserting mechanism, whenever actuated by a lifted strip. 70

3. In a power press, the combination of suction cups, strip inserting arms associated therewith, mechanism for simultaneously moving said arms, and arm arresting dogs, one associated with each suction cup and arm, and normally located in position to arrest movement of an associated arm, each dog having strip actuated means for moving said dog out of its effective position, whenever said means is actuated by a lifted strip. 75 80

4. In a power press, the combination of suction cups, strip inserting arms associated therewith, each arm having a collar thereon, mechanism for simultaneously moving said arms, and arm arresting dogs, one associated with each suction cup and arm, and normally located in position to engage the collar of an associated arm, and thereby arrest movement of an associated arm. 85 90

5. In a power press, the combination of suction cups, strip inserting arms associated therewith, mechanism for simultaneously moving said arms, arm arresting dogs, one associated with each suction cup and arm, and normally located in position to arrest movement of an associated arm, strip actuated, dog engaging pins, one pin for each dog, operating to move said dog out of its effective position whenever the pin is actuated by a lifted strip. 95 100

6. In a power press, the combination of suction cups, strip inserting arms associated therewith, there being a collar on each arm, mechanism for simultaneously moving said arms, arm arresting dogs, one associated with each suction cup and arm, and normally located behind an associated collar in position to arrest movement of an associated arm, and strip actuated, dog engaging pins, one pin for each dog, operating to move said dog out of its effective position whenever the pin is actuated by a lifted strip. 105 110

7. In a power press, the combination of suction cups, strip inserting arms associated therewith, mechanism for simultaneously moving said arms, arm arresting dogs, one associated with each suction cup and arm, and normally located in position to arrest movement of an associated arm, a bracket, strip actuated, dog engaging pins, one pin for each dog, and a collar secured on each pin and normally resting on a bracket, and supporting one end of the pin in the path of movement of the strips. 115 120 125

8. In a power press, the combination of two suction cups, two strip inserting arms, one associated with each suction cup, arm actuating means having one element to 130

which both arms are fixedly connected, arm arresting dogs, one associated with each suction cup and arm and lying in the path of movement of a fixed part of an associated arm, and a strip actuated, dog lifting pin for each dog operating to lift said dog out of its effective position.

9. In a power press, the combination of two suction cups, two strip inserting arms, one associated with each suction cup, arm actuating means having one element to which both arms are fixedly connected, said actuating means including a yielding arm actuating element, arm arresting dogs, one associated with each suction cup and arm, and lying in the path of movement of a fixed part of an associated arm, and a strip

actuated, dog lifting pin for each dog, operating to lift said dog out of its effective position.

10. In a power press, the combination of two suction cups, two strip actuating arms, one associated with each suction cup, there being a collar on each arm, arm actuating means having one element to which both arms are fixedly connected, said actuating means having a yielding, arm actuating element, arm arresting dogs, one associated with each suction cup and arm and lying in the path of movement of the collar on an associated arm, and a strip actuated, dog lifting pin for each dog, operating to lift said dog out of its effective position.

CHARLES D. McDONALD.
